BOILER PLUG.

Application filed May 3, 1924. Serial No. 710,856.

This invention pertains to a clean-out plug for boilers and the like.

Whereas the usual clean-out plug used on boilers is adapted to screw tightly therein, 5 the threads become corroded and rusted making it difficult to unscrew the plug, or replace it. Furthermore the screw threads in the boiler become worn and broken so that eventually it is necessary to retap the boiler 10 and use a larger plug.

It is the object of this invention to provide a plug having a removable core so that the plug can remain screwed into the boiler permanently, access to the interior of 15 the boiler being had through an opening in the plug which is closed by a core held in place by suitable screw thread segments with respect to the plug, said screw threads being protected from corrosion by the water by a 20 ground ball joint and beveled seat.

Other features of the invention with respect to the locking and wedging construction as well as a means for preventing the movement of the core from the closed position will be herein after more fully set forth 25 and described.

The value of this invention resides in the fact that it eliminates the danger of a plug blowing out causing damage and often personal injury. This has been occasioned heretofore, where in screwing the plug in place 30 after having been removed, the threads are crossed, causing some threads to be stripped so as to weaken them and permit the high pressure of the boiler to cause the blowout with the consequent danger and damage. This invention eliminates that danger by 35 reason of the fact that the screw threaded plug remains permanently in the boiler, access being had only through the removable core.

The full nature of the invention will be understood from the accompanying drawings and the following description and 40 claims.

Fig. 1 is a plan view of the plug with the core in unlocked position. Fig. 2 is the same as Fig. 1, showing the plug with the core in locked position thereon and provided with 45 a retaining key. Fig. 3 is a section taken on the line 3-3 of Fig. 2. Fig. 4 is a side elevation of the closing core. Fig. 5 is a central vertical section through the plug taken on the line 5-5 of Fig. 1 with the core 50 removed.

In the drawing there is shown a plug for a boiler or the like having a threaded portion 10 adapted to screw into a tapped opening in the boiler, said threaded portion being surmounted with an annular outwardly extending head 11. The plug is in the form of a shell having a relatively large opening 12 which is adapted to be closed by the core 13. Adjacent said opening and contained within the head 11 there is provided a beveled seat 14 adapted to receive a correspondingly ball portion 15 on the cap so as to permit a ground fit to be had therebetween.

The head of the plug is provided with oppositely disposed and inwardly extending 70 thread segments 16, each of which extends a quarter of the distance about the innerperiphery of the head. Said thread segments are tapered as best shown in Fig. 5, to give a substantial pitch. As shown here- 75 in, they are formed with a half inch pitch.

The core is provided with corresponding outwardly extending thread segments 17 formed about the periphery thereof and diametrically opposed to each other. Said 80 thread segments 17 likewise extend a quarter distance about the periphery, and lie adjacent the bevel sealing portion 14, the same having an opposite and corresponding pitch as shown in Fig. 4. This arrangement is 85 such that the core may be inserted in the head of the plug so as to be seated upon the beveled portion 14 thereof, the thread segments 17 dropping into position between the ends of the thread segments 16 on the plug. 90 Therefore, upon turning the core within the plug head the segments 17 and 16 will interlock as shown in Figs. 1 and 2, and by reason of their respective pitches will screw together so that the tighter the cap is turned 95 the more firmly they will be screwed into position, causing the ground bevel portion 14 and ball 15 to be more firmly and securely sealed to withstand leakage and pressure.

The core is further provided with a head 100 18 having a centrally disposed hexagonal recess 19 for receiving a suitable wrench. It will be obvious therefore that on applying the wrench thereto and turning the core a quarter turn in one direction it will be interlocked in the plug so as to close the opening therein, and the greater the pressure exerted in turning the core the more firmly it will become seated for withstanding leakage. On the other hand by turning the core a 110

quarter turn in the opposite direction it will become freed and can be readily removed from the plug so that access may be had to the interior of the boiler.

- 5 A suitable means may be employed for limiting the turning movement of the core in closing position, which is herein shown as comprising the pin 20 which extends through the ends of the segments 16 away from the receiving ends thereof so that it will be impossible to turn the core beyond the locking engagement of screw threads. However the thread segments are so formed as to cause them to screw together when the 10 cap is partially turned to locking engagement so that there will be sufficient latitude permitted for further turning it to compensate for wear.

For retaining the core in locked position, 20 or rather for preventing it from being turned so as to be released from the plug, there is provided a tapered locking key pin 21 having a head 22 adapted to be inserted through a tapered tangential opening 23 in the head 11. After the core is turned into 25 locking engagement with the head the pin may be freely passed through said opening and locked therein by the end piece 24, which falls into locking position by gravity because of its off center pivoted connection 25. With respect to the locking pin, it will be observed that it is so positioned with respect to the core as to permit the core to be tightened but prevent its becoming loosened.

35 The invention claimed is:

1. A plug for boilers or the like having an opening therethrough, a bevel seat adjacent said opening, a core having a ball portion adapted to rest on said seat and having a 40 ground fit therewith, inwardly formed grooves having their open ends spaced apart within said plug externally of said opening and increasing in thickness from one end to the other so as to have a suitable pitch, and corresponding oppositely disposed thread 45 segments formed on said core externally of said ball portion and tapering in thickness from one end to the other so as to have a corresponding pitch, said segments being so arranged that said core may be inserted in said plug for closing said opening and turned therein so that the segments will engage and wedge in said grooves into locking 50 position.

- 55 2. A plug construction, comprising a tubular body having one end suitably formed for boiler mounting and a central opening therethrough, a laterally directed flange opposite the mountable end of the body and 60 including a circular valve seat at the junction thereof, a plurality of inwardly and radially extending overhanging portions integral with the flange and circularly connected together for forming protected and 65 enclosed segmental thread grooves with the

flange face, each of said overhanging portions having an inclined face and arranged in spaced relation with each other, and a cap having a circular valve forming portion at the bottom thereof, a tool engageable portion at the top thereof, and a plurality of outwardly and radially extending thread forming segments in spaced relation with each other and intermediate the top and bottom, each thread forming segment 70 having an outer inclined face for wedging engagement with the inclined face of the groove, said overhanging portions being spaced apart sufficient to permit longitudinal axial seating of the thread forming segments and valve seating prior to rotational locking.

3. A device of the character defined by claim 2, characterized by the sealing cap being so arranged that no portion of it 85 projects laterally or longitudinally beyond the plug body when seated.

4. A plug construction of the character defined by claim 2, characterized by the valve and valve seat being complementarily 90 formed, one being a bevelled surface and the other a ball surface.

5. A plug for boilers or the like having an opening therethrough, a bevel seat externally of and adjacent said opening, a core having a ball portion adapted to rest in said seat and having a ground fit therewith, inwardly formed grooves in said plug externally of 95 said opening width from one end to the other so as to have a suitable pitch, corresponding and oppositely disposed thread segments formed on said core tapering in thickness from one end to the other so as to have a corresponding pitch, said segments being so arranged that said core may be inserted in said plug for closing said opening and turned therein so as to engage within said grooves and wedge into locking position, a key member adapted to be engaged in said plug upon said core being locked in position therein so as to prevent it being turned to unlocking position, and a lug pivotally mounted off center on one end of said member so as to be capable of dropping to locking position by gravity.

6. A device of the character defined by claim 2, characterized by the addition of means positioned in the reduced portion of one of the grooves for limiting threading movement of the cap therein.

7. A device of the character defined by claim 2, characterized by the plug body including a substantially tangentially arranged recess communicating with the locking groove, and the addition of a key receivable by said groove and tangentially engaging said cap for preventing the unthreading movement of the same.

8. A plug construction, comprising a tubular body having an exteriorly threaded 130

- portion at one end, a lateral enlargement at the opposite end including a circular valve seat concentric with the tubular body at the junction therewith, and a plurality of overhanging inwardly and radially extending spaced portions circularly connected together, each of said portions forming with the face of the lateral enlargement a plurality of arcuate and protected grooves, each 5 of said arcuate grooves having pairs of walls relatively inclined to each other, and a cap having its top formed for tubular engagement and its bottom provided with a circular valve for seating engagement with the valve seat, said valve and valve seat being 15 cooperatively formed to provide a fluid and pressure tight joint, and a similar number of similarly spaced radially extending thread forming sections on the cap each having a pair of relatively inclined faces whereby 20 partial relative rotation between the cap and body wedgingly secures the cap and body together in fluid and pressure tight relation.

In witness whereof, we have hereunto affixed our signatures.

FRED K. MURPHY.
